UNITED STATES PATENT OFFICE.

GEORGE M. JOHNSON, OF McDONALD, PENNSYLVANIA.

MINE-SHAFT SAFETY DEVICE.

1,333,921.

Specification of Letters Patent. Patented Mar. 16, 1920.

Application filed July 23, 1918. Serial No. 246,367.

To all whom it may concern:

Be it known that I, GEORGE M. JOHNSON, a citizen of the United States, residing at McDonald, in the county of Washington and State of Pennsylvania, have invented 5 certain new and useful Improvements in Mine-Shaft Safety Devices, of which the following is a specification.

This invention relates to mine shaft safety 10 device for use in connection with lander and car feed controlling mechanisms for mine cages, and has for its object to provide means, in a manner as hereinafter set forth, for simultaneously shifting the lander mechanism and the trip element of a car feed 15 controlling mechanism to a position, to enable the mine cage during its elevating or lowering movement to clear said lander mechanism and trip element, under such conditions not interrupting the passage of the 20 cage or injuring the car feed controlling mechanisms.

A further object of the invention is to provide a safety device for the purpose set 25 forth including means having provisions to prevent the operation of the trip element referred to when the landers of a lander mechanism are shifted by the mine cage on the ascent of the latter.

30 Further objects of the invention are to provide a safety device for the purpose set forth, which is simple in its construction and arrangement, conveniently operated at a landing, strong, durable, efficient in use, 35 readily set up and comparatively inexpensive. With the foregoing and other objects in view this invention consists of the novel construction, combination and arrangement of parts, as hereinafter more 40 specifically described and illustrated in the accompanying drawings, wherein is shown an embodiment of the invention, but it is to be understood that changes, variations and modifications can be resorted to which 45 come within the scope of the claims hereunto appended.

In the drawings wherein like reference characters denote corresponding parts throughout the several views:

50 Figure 1 is a plan view of a safety device for the purpose set forth showing the adaptation of such device in connection with lander and car feed controlling mechanisms.

Fig. 2 is an elevation, partly in section, of

the safety device showing the adaptation 55 thereof in connection with lander and car feed controlling mechanisms.

Fig. 3 is a section on line III—III, Fig. 2.

Fig. 4 is a sectional detail.

The safety device is employed at the landings arranged at the top and bottom and intermediate the top and bottom of a mine shaft and is adapted when actuated to shift the landers of a lander mechanism and a tripping element for a car feed controlling 60 mechanism, the tripping element separately or simultaneously with the landers, clear of the path of a mine cage during its ascent or descent, whereby the movement of the cage will not be retarded or interrupted or the 65 cage injured, or whereby the car feed controlling mechanism will not be injured during the ascent of the cage or the landers on the descent of the cage.

Referring to the drawings in detail 1, 2 75 and 3, denote the cross-ties of a landing, which may be at the top or bottom or intermediate the top or bottom of the mine shaft, and upon which is mounted a car feed controlling mechanism referred to generally by 80 the reference character A, said mechanism being somewhat similar in construction to that disclosed in my application for Letters Patent Serial No. 224,743, Mar. 26, 1918, difference residing in the construction of 85 and operation of the car stop blocks and the means connected to the blocks for shifting them. Such construction of stop blocks and the means connected directly with the stop blocks for operating them will be made the 90 subject matter of a subsequent application, and as no claim is made herein to the car feed controlling mechanism which includes the stop blocks and the means directly connected therewith for operating said blocks, 95 it is thought unnecessary to specifically describe said mechanism, other than reference to the rock shaft 4, upon which is mounted an oscillatory and longitudinally movable trip arm or crank 5, which is adapted to be 100 tripped by the mine cage to rock the shaft 4, to actuate said mechanism. The track rails at the landing are arranged at 6, 7.

The tie or support 1, has its outer face formed with a pair of pockets 8, in which 105 are shifted the shouldered upper ends 9, of a pair of landers 10, secured on a rock-shaft 11, journaled in bearings 12, fixed to a sup-

port 13, arranged below the tie 1. The shaft 11, at one end has a counter-weighted crank arm 14, which normally retains the landers 10, clear of the pockets 8, and in the path of travel of the mine cage. The other end of the shaft 11, has a crank arm 15, provided at its upper end with a pin 16, which extends through a curved slot 17, formed in the angular forward end 18, of a link 19, provided with a pin 20, extending through the slotted lower end 21, of a crank arm 22, carried by rock shaft 23, mounted in brackets 25, which are secured to the tie 1, at the rear thereof. The rear end of the link 19, is pivotally connected as at 26, to an adjustable actuating lever 27, which is pivotally connected at its lower end, as at 28, to a bracket 29, secured to a support 30. The link 19, is pivotally connected to the actuating lever 27, near the lower end thereof. The lever 27, extends up through a pair of apertured lock-bars 31, and can be retained in adjusted position by stop pins 32, which extend through the bars 31.

When the lever 27, is shifted to the position shown in Fig. 3, the landers 10, have their upper ends moved into the pockets 8, whereby the landers 10, will be clear of the path of travel of the mine cage. The shifting of the lever 27, is against the action of the counterweighted crank 14.

The tie 1, is cut away at 33, to form a seat or pocket for the trip arm or crank 5, to receive the latter when depressed. The arm 5, normally extends into the path of travel of the mine cage so that it can be shifted by the latter to rock the shaft 4. The arm 5, has a hub 34, which is keyed upon the shaft 4 as at 35, and is capable of being shifted longitudinally on said shaft 4, whereby the arm 5, can be moved to a position clear of the path of travel of the mine cage. A stop 35, is provided to limit inward movement of the hub 34. The arm 5, is normally in an elevated position.

The hub 34, near its inner end has a peripheral groove 36, into which extends the angular end 37, of a shifting arm 38, for the trip arm 5. The shifting arm 38, is employed for moving the hub 34, inwardly and outwardly in a longitudinal direction on the shaft 4, and is also employed for limiting the outward movement of the hub 34, and further for maintaining the trip arm 5, in the path of travel of the mine cage. When the shifting arm 38, is actuated to move the hub 34, inwardly on the shaft 4, the trip arm 5 will be carried inwardly to such an extent that it will be clear of the path of travel of the mine cage, whereby the arm 5, will not be tripped to actuate the car feed controlling mechanisms and further not interfere with the travel of the mine cage.

The arm 38, is fixed to the upper end of an actuating shaft 39, which is supported in the

tie 1, and extends above and below the same. The lower end of the shaft 39 has a crank arm 40, which is loosely connected as at 41, to a crank arm 42, projecting downwardly from the shaft 23. By this arrangement when the lever arm 27, is moved to the position shown in Fig. 3, the shaft 23, will be actuated carrying the crank arm 42, therewith, which in turn will shift the crank arm 40, and actuate the shaft 39, whereby the shifting arm 38 will be moved inwardly carrying the trip arm 5 therewith.

When the lever 27, is released the counterweighted crank 14, will shift the shaft 11, and through the connections between said shaft 11, lever 27, shaft 23, and shaft 39, the lever 27 will be moved to a position opposite to that shown in Fig. 3, whereby the landers 10 will be projected into the path of travel of the mine cage, and the shaft 39, actuated to move the shifting arm 38, outwardly, which will shift the trip arm 5, to position in the path of travel of the mine cage.

The curved slot 17, in the angular forward end 18, of the link arm 19, is of sufficient length to permit of the shifting of the pin 16, therein, without operating link 19, when the lander elements 10 are shifted by the cage on its ascent, by this arrangement the landers are operated independently of the shifting arm 38.

What I claim is:

1. A safety device for the purpose set forth comprising the combination with the trip element of a car feed controlling mechanism, said element normally positioned in the path of travel of the mine cage, of means operatively connected with said element and adapted when actuated to shift the element from and to normal position, a stop for limiting the inward movement of said element, and said means limiting the outward movement of said element.

2. A safety device for the purpose set forth comprising the combination with a counterweighted shaft provided with lander elements, and an oscillatory and longitudinally movable trip element for a car feed controlling mechanism, of means operatively connected with said element and shaft for simultaneously shifting them to move the said elements out of the path of travel of a mine cage.

3. A safety device comprising a rock-shaft, an oscillatory and longitudinally movable trip element mounted on said shaft, a vertically disposed shaft, an oscillatory shifting arm carried by the vertical shaft and engaging in said element for shifting it from and to the path of travel of a mine cage, a counterweighted rock-shaft, lander elements carried thereby and normally projecting in the path of travel of a mine cage, and a means operatively connected with said vertical shaft and said counterweighted

rock-shaft for actuating them to simultaneously shift them clear of the path of travel of a mine cage.

4. A safety device comprising an oscillatory and longitudinally shiftable trip element for a car feed controlling mechanism, said element normally projecting in the path of travel of a mine cage, an oscillatory shifting arm engaged in said element and adapted when operated to move said element from and to the path of travel of a mine cage, a vertically disposed shaft having said arm connected to the upper end thereof, a crank arm at the lower end of said shaft, and means for actuating the crank arm to operate the shaft to shift said arm to move said element from and to the path of travel of a mine cage.

5. A safety device for the purpose set forth comprising the combination with a trip element of a car feed controlling mechanism, said tripping element normally extending into the path of travel of a mine cage, and a lander mechanism including lander elements normally positioned in the path of travel of a mine cage, of means operatively connected with said element and mechanism for shifting said elements simultaneously to move them out of the path of travel of a mine cage.

6. A safety device for the purpose set forth comprising the combination with the trip element of a car feed controlling mechanism, said tripping element normally extending into the path of travel of a mine cage and a lander mechanism including lander elements normally positioned in the path of travel of a mine cage, a shifting mechanism operatively connecting said element and lander mechanism together whereby when the shifting mechanism is actuated said trip element and lander elements will be shifted clear of the path of travel of a mine cage, and a lever for operating said shifting mechanism.

7. A safety device for the purpose set forth comprising the combination with the trip element of a car feed controlling mechanism, said tripping element normally extending into the path of travel of a mine cage and a lander mechanism including landers normally positioned in the path of travel of a mine cage, a shifting mechanism operatively connecting said element and lander mechanism together whereby when the shifting mechanism is actuated said trip element and lander mechanism will be shifted clear of the path of travel of a mine cage, and a lever for operating said shifting mechanism, and said lander mechanism including a counterweighted shaft for shifting said element and lander mechanism in the path of travel of a mine cage when said lever is released.

8. A safety device for the purpose set

forth comprising the combination with the trip element of a car feed controlling mechanism, said tripping element normally extending into the path of travel of a mine cage and a lander mechanism including landers normally positioned in the path of travel of a mine cage, a shifting mechanism operatively connecting said element and lander mechanism together whereby when the shifting mechanism is actuated said trip element and lander mechanism will be shifted clear of the path of travel of a mine cage, and a lever for operating said shifting mechanism, said shifting mechanism pivotally and adjustably connected with the lander mechanism and pivotally and slidably engaging with said trip element.

9. A safety device for the purpose set forth comprising an oscillatory and a longitudinally shiftable trip arm provided with a hub formed with a peripheral groove, a shifting arm having one end engaging in said groove for longitudinally shifting the trip arm when the shifting arm is actuated, a shaft for actuating the trip arm, and means operatively engaging with one end of said shaft for operating it to actuate said shifting arm.

10. A safety device for the purpose set forth comprising an oscillatory and a longitudinally shiftable trip arm provided with a hub formed with a peripheral groove, a shifting arm having one end engaging in said groove for longitudinally shifting the trip arm when the shifting arm is actuated, a shaft for actuating the trip arm, means operatively engaging with one end of said shaft for operating it to actuate said shifting arm, and a lever for operating said means.

11. A safety device for the purpose set forth comprising an oscillatory and a longitudinally shiftable trip arm provided with a hub formed with a peripheral groove, a shifting arm having one end engaging in said groove for longitudinally shifting the trip arm when the shifting arm is actuated, a shaft for actuating the trip arm, means operatively engaging with one end of said shaft for operating it to actuate said shifting arm, a lever for operating said means, and a stop for limiting the inward movement of said hub, said shifting arm limiting the outward movement of said hub.

12. A safety device for the purpose set forth comprising a trip element shifting arm, a lander element shifting mechanism, and an actuating mechanism operatively connected with said lander mechanism and shifting arm for simultaneously operating them, said actuating mechanism having provisions to prevent the operation thereof when the lander mechanism is operated by a mine cage on the ascent of the latter.

13. A safety device for the purpose set

forth comprising the combination with a counterweighted shaft provided with lander elements, and an oscillatory and longitudinally movable trip element for a car feed controlling mechanism, of means operatively connected with said element and shaft for simultaneously shifting them to move the said elements out of the path of travel of a mine cage, said means having provisions to prevent the operation thereof when the lander elements are shifted by a mine cage on the ascent of the latter.

14. A safety device comprising a rock-shaft, an oscillatory and longitudinally movable trip element mounted on said shaft, a vertically disposed shaft, an oscillatory shifting arm carried by the vertical shaft and engaging in said element for shifting it from and to the path of travel of a mine cage, a counterweighted rock shaft, lander elements carried thereby and normally projecting in the path of travel of a mine cage, and a means operatively connected with said vertical shaft and said counterweighted rock-shaft for actuating them to simultaneously shift them clear of the path of travel of a mine cage, said means having provisions to prevent the operation thereof when the lander elements are shifted by a mine cage on the ascent of the latter.

15. A safety device for the purpose set forth comprising the combination with the trip element of a car feed controlling mech-

anism, said tripping element normally extending into the path of travel of a mine cage, and a lander mechanism including lander elements normally positioned in the path of travel of a mine cage, of means operatively connected with said element and mechanism for shifting said elements simultaneously to move them out of the path of travel of a mine cage, said means having provisions to prevent the operation thereof when the lander elements are shifted by a mine cage on the ascent of the latter.

16. A safety device for the purpose set forth comprising the combination with the trip element of a car feed controlling mechanism, said tripping element normally extending into the path of travel of a mine cage and a lander mechanism including lander elements normally positioned in the path of travel of a mine cage, a shifting mechanism operatively connecting said element and lander mechanism together whereby when the shifting mechanism is actuated said trip element and lander elements will be shifted clear of the path of travel of a mine cage, and a lever for operating said shifting mechanism, said means having provisions to prevent the operation thereof when the lander elements are shifted by a mine cage on the ascent of the latter.

In testimony whereof I affix my signature.

GEORGE M. JOHNSON.
